UNITED STATES PATENT OFFICE.

FREDERICK H. CUMMER, OF GREAT NECK, NEW YORK.

PORTRABLE DRIER.

Application filed May 16, 1921. Serial No. 469,796.

To all whom it may concern:

Be it known that I, FREDERICK H. CUMMER, a citizen of the United States, residing at Great Neck, Long Island, in the county 5 of Nassau and State of New York, have invented certain new and useful Improvements in Portable Driers, of which the following is a specification.

This invention relates to portable driers 10 such as are used for heating crushed rock or other materials used in laying roadways or pavements or for other purposes.

The object of the invention is to provide 15 an improved portable drier which is of simple form; is strong and heavy enough for its intended uses, but without carrying excessive weight; which enables the material to be heated or dried to be fed or charged into the drier without disturbing the circulation or flow of the hot gases; and which is highly efficient in use.

Other objects of the invention are in part obvious and in part will appear more in detail hereinafter.

25 In the drawings Fig. 1 is a side elevation, partly broken out and in section, of a drier embodying the invention; Fig. 2 is an end elevation from the left in Fig. 1; Fig. 3 is a detail sectional view on the line 3—3, Fig. 30 2, the operating or driving mechanism being omitted; and Fig. 4 is a sectional elevation on the line 4—4, Fig. 1.

The drier shown in the drawings comprises a suitable strong and heavy frame 1, 35 which may be of any construction and is mounted upon the rear wheels 2 and front wheels 3, which front wheels may be suitably arranged for steering. At one end of the frame, such as at the rear end, said frame 40 is provided with a depending supporting frame 4 in which is mounted a driving motor, such as the internal combustion engine 5 arranged to turn a shaft 6 provided with a fly wheel 7 and a sprocket wheel 3.

45 The frame also supports a hollow drum or cylinder 9 made of sheet metal provided internally with a plurality, five being shown, of longitudinally extending lifting members or baffles 10 formed of channel irons with 50 the webs extending radially, as shown in Fig. 4.

The axis of the cylinder is inclined downwardly very slightly from the feeding toward the discharge end, say an inclination 55 of one-eighth ($\frac{1}{8}$) of an inch per foot, so that when said cylinder rotates the material

therein will be gradually moved toward the discharge end. Cylinder 9 is provided with tracks, such as T rails 11, extending circumferentially around the same at or near 60 its opposite ends, said rails resting upon pairs of idle rollers 12 in the frame. One end of the cylinder is provided with driving means such as the ring gear 13 meshing with a pinion 14 on a short shaft 15 carrying a large gear 16 driven by a pinion 17 on a second shaft 18 which is provided with a sprocket wheel 19 from which the chain 20 extends to and around the driving sprocket wheel 8, before referred to.

70 Suitable means is provided for subjecting the contents of the cylinder to gases for drying or heating the same. As illustrated, the front end of the frame is provided with a heating furnace indicated generally at 21 75 and comprising a sheet metal jacket lined with fire brick, as indicated at 22. In the bottom of the furnace are the grate bars 23 and at one end the firing door 24. The discharge end of the cylinder projects slightly 80 into the furnace, where it terminates in front of a laterally extending inclined chute or hopper 25 provided at one side of the machine with a valve or door 26 actuated by the hand lever 27. One side of the chute 85 or hopper is formed by a transverse wall 28 which is convex at its top, as indicated in Fig. 4. This wall prevents the material being heated from getting over into the furnace and also prevents the fire from flowing 90 over into the discharge chute.

The gases from the fire travel rearwardly through the hollow rotating cylinder and out through a stack at the feeding end thereof. The stack, indicated at 28^a, is mounted 95 upon the upper portion of a hollow casing 29, shown in detail in Fig. 3, and is usually hinged thereto, as at 30, to enable it to be turned down into horizontal position when traveling over a roadway. One portion of 100 the hollow casing, marked 31, extends into the open end of the hollow cylinder and beyond the ring gear 13 thereof. The bottom of the casing is provided with a diagonally extending or inclined channel 32 formed by 105 the walls 32^a, leading from the feeding opening 33 into the bottom of the cylinder. Casing 29 including the stack and feed chute 32 are mounted upon brackets or supports 34 on the stationary frame.

110 With this arrangement the crushed rock or other material is dumped into the open

end of chute 32 from which it flows into the cylinder. The power engine 5 is driven so as to slowly rotate said cylinder. The material entering the cylinder is lifted by the 5 baffles or lifting plates 10 thereof, carried around in the direction of the arrow A, Fig. 4, and when said baffles reach the upper portion of the cylinder the material is allowed to fall. The rotation and inclination of the 10 cylinder cause the material to gradually work its way to the discharge end where it is delivered to the chute or hopper 25 and is taken out as required by opening the door 26. The hot gases from the furnace travel 15 through the cylinder in a direction opposite to the travel of the road material therein and are discharged through the stack, but the draft through the stack is such that no hot gases come out through the feeding 20 opening 33, but said opening can be left open, if desired.

The drier described is of simple form and is quite efficient for its intended purpose, is strong and durable, and at the same time 25 does not include excessive weight.

What I claim is:

1. A drier for road material, comprising a frame and wheels therefor, a rotating cylinder inclined downwardly on said frame toward one end thereof, a furnace spaced 30 from the lower end of said cylinder to provide a material discharge space between said cylinder and furnace, and means at the upper end of said cylinder whereby material may be introduced thereinto.

2. A drier for road material, comprising a frame and wheels therefor, a rotating cylinder inclined downwardly on said frame toward one end thereof, a furnace spaced 35 from the lower end of said cylinder to provide a material discharge space between said cylinder and furnace, means at the upper end of said cylinder whereby material may be introduced thereinto, and a transverse 40 wall lying between said furnace and material discharge space to prevent the escape of fire from said furnace.

In testimony whereof I hereby affix my signature.

FREDERICK H. CUMMER.
